(57) **CLAIM**

The ornamental design for a rimless eyeglass components, as shown and described.

DESCRIPTION

FIG. 1 is a front perspective view of the rimless eyeglass components of the present invention;
FIG. 2 is a front elevational view thereof;
FIG. 3 is a rear elevational view thereof;
FIG. 4 is a right-side elevational view thereof, the left-side elevational view being a mirror image thereof;
FIG. 5 is a bottom plan view thereof; and,
FIG. 6 is a top plan view thereof.
Phantom lining, where utilized, is for illustrative purposes only and is not intended to limit the claimed design to the features shown in phantom.
